UNITED STATES PATENT OFFICE.

ANTON DUPPLER, OF JERSEY CITY, NEW JERSEY, ASSIGNOR, BY DIRECT AND MESNE ASSIGNMENTS, TO PHOEBUS H. ALEXANDER, OF NEW YORK, N. Y., AND COMPOUND MAGNET BRAKE COMPANY, OF NEW JERSEY.

RAILWAY-BRAKE.

SPECIFICATION forming part of Letters Patent No. 670,419, dated March 26, 1901.

Application filed October 17, 1900. Serial No. 33,367. (No model.)

To all whom it may concern:

Be it known that I, ANTON DUPPLER, a citizen of the United States, residing at Jersey City, in the county of Hudson and State of 5 New Jersey, have invented an Improvement in Railway-Brakes, of which the following is a specification.

The object of my invention is to provide for the application upon a car or series of cars of 10 a manually-operated braking mechanism arranged to coöperate with an electrically-operated braking mechanism in the following way—that is to say, a movement of the common handle for controlling both systems applies a moderate braking effort through the 15 hand-operated mechanism. The further movement of such handle cuts in the electrically-operated braking mechanism without in any way further affecting the hand-operated 20 braking mechanism until the full power of the electrically-operated braking mechanism has been applied, and then a still further movement of such handle increases the braking effort applied by the hand-operated 25 braking mechanism, while the electrically-operated braking mechanism still remains at its maximum. It is of course immaterial whether the effort applied by both mechanisms be exerted upon the same or upon different braking- 30 shoes, and while in the accompanying drawings I have shown both systems as applied to a common set of braking-shoes I do not, however, limit myself to that arrangement. I have found that by the use of a series 35 of magnets with their armatures normally spaced at unequal distances from such magnets and operating in such a way that such armatures contact with their magnets *seriatim* in the application of the braking effort 40 a mechanical pawl for holding the brakes at any point to which they have been applied may be dispensed with, as the very nearly closed magnetic circuit between the armature and its magnet last to come in contact tends 45 to maintain such brakes at the point to which they have been thus applied, the effort which is required to rupture such nearly-closed magnetic circuit operating to maintain such brakes at that point in their application where 50 the last armature has contacted with its mag-

net. I have also found it desirable in arranging such armatures and their magnets to so assemble them and connect them to a common support and to a common actuating device that any one of such armatures or any 55 one of such magnets may be removed from the system without disturbing any of the remaining armatures or magnets or their operative connections. By this arrangement inoperative or defective parts may be readily 60 replaced without disturbing the other operative features of the mechanism.

In another pending application I have shown a system of braking in which the energizing-coils of the electrically-operated 65 braking mechanism are located in series, and for regulating the braking effort I regulate the potential of the current supplied to the terminals of such energizing-coils. I have found that it is often desirable to omit some 70 of the coils, except in cases of emergency where they may all be needed. For that reason I arrange such energizing-coils in parallel, and as each energizing-coil is cut into circuit it is retained in the energizing-circuit until 75 the release of the brakes by means of the handle, when they are cut out of circuit, the energizing-coils are cut in *seriatim*, and of course cut out in a similar way, but in the reverse order. Each one of such coils, of 80 course it will be understood, is wound to stand the full potential of the supply-circuit, and the point to which the brakes are drawn, as well as the braking effort, is regulated by the number of coils cut into circuit. When the 85 energizing-coils are connected up in parallel, the burning out of any one coil does not render the others inoperative.

The accompanying drawings, illustrating my invention, are as follows:

Figure 1 is a side view, and Fig. 2 a plan view, of a portion of a car with my braking system applied to a single pair of wheels on such car. In each of such figures only such parts are shown as are necessary to indicate 95 in diagrammatic relation the essential features of my invention. Figs. 3 and 4 are respectively horizontal and vertical longitudinal sections through the axis of the system of magnets which I make use of in the electric- 100

ally-operated mechanism as viewed from the top and side of the car, while Fig. 5 is a vertical transverse section taken along the line $x'y$ of Fig. 3. Fig. 6 is an elevation showing 5 diagrammatically the arrangement of the actuating devices of my braking mechanism as they would appear if removed from the car and supported in operative relation to each other and as viewed from the right in Figs. 1 10 and 2. Fig. 7 is a plan view of the mechanism carried by the shaft b^2 . Fig. 8 is a diagrammatic view of the energizing-coils of my braking-magnets and of the circuit connections thereto.

15 Similar letters refer to similar parts throughout the several views.

Referring to the drawings, A represents the platform of a car, from which there may be suspended in any suitable way the case C, 20 containing the electrically-operated mechanism consisting in a series of magnets and armatures. W W are the wheels of the car, to which the brake-shoes are applied in the manner and by mechanism yet to be explained for 25 producing the braking effort. The brake-shoes f are secured to a brake-beam a^8 , which may receive any suitable support of the character found in brakes generally. From a point near the center of this brake-beam a^8 and 30 pivoted thereto there extends a connecting-link a^6 , which in turn is pivotally connected with the lever a^6 . This lever a^6 is pivotally supported at t' from the under side of the car by means of any suitable mechanism, so as 35 to swing in a practically horizontal plane. From this lever a^6 there extends a rod a , pivotally connected therewith and connected at its right-hand end to a chain c , arranged in the usual way to be wound upon the lower 40 end of the brake-spindle b' , which is rotated in the manner to be explained. It is desirable to provide this brake-spindle b' with a ratchet-wheel w , rigidly secured thereto, and 45 a suitable pawl p , coöperating with such ratchet-wheel w in the well-known way. In case of a failure of the electrically-operated system the ratchet-wheel w and the pawl p may be used in the ordinary way to lock the 50 brakes to any point to which they have been applied by means of the hand-operated mechanism. A brake-staff b , provided with a handle h , is supported in any suitable bearings, and upon this brake-staff b there is secured the gear g , engaging the rack g' on the bar 55 a' . A slot i' in the left-hand end of this bar a' is provided in order that this bar a' may move longitudinally over a considerable portion of its throw without carrying with it the contact-making bar a^2 . This contact-bar 60 a^2 has two pins l , extending therefrom, working in the slot i' in the rack-bar a' , and by means of which the horizontal movement of this rack-bar a' is communicated to this contact-bar a^2 . One terminal of each of the energizing-coils $M' M^2 M^3 M^4$ for the magnets contained in the case C is connected to the source of electric energy B, from which also

a connection is made to the contact-spring s , all as clearly indicated in diagram in Fig. 8. The other terminal of coil M' is connected 70 with the contact s' , of coil M^2 with the contact s^2 , of coil M^3 with the contact s^3 , and of coil M^4 with the contact s^4 , whereby when the gear g is rotated clockwise from the position indicated in Figs. 1 and 2 each one of the energizing-coils $M' M^2 M^3 M^4$ is connected in circuit with a source of electric energy B and in the order named. Each one of such energizing-coils when it has been cut in is retained in operative circuit until by the return 80 movement of the gear g it is cut out of circuit and the brakes are released. This gear g meshes in turn with a gear g^4 (not seen in Fig. 2, but seen in Figs. 1 and 6) and located immediately beneath the gear g^2 and of the same size. The gears g^2 and g^4 are secured rigidly upon the shaft b^2 . The gear g^2 engages in turn the gear g^3 , rigidly secured upon the brake-spindle b' . A projection g , formed on this gear g^2 , prevents a complete rotation 90 in either direction of the gear g^2 and serves as a stop to limit the motion of the handle h and the spindle b' , in the manner clearly indicated. Immediately above this gear g^2 there is shown a sector q^2 , rigidly secured upon shaft b^2 . The outer periphery of this sector q^2 coöperates with the sector q' , rigidly secured upon the brake-spindle b' in such a way as to prevent the rotation of the brake-spindle b' , while the sector q^2 engages the 100 sector q' . As indicated in dotted lines in Figs. 2 and 7 there are no teeth upon the gear g^2 over that portion of the periphery thereof immediately beneath the sector q^2 . The operation of this portion of my braking mechanism is as follows: Starting with the several parts in the positions indicated in Figs. 1 and 2 a rotation of the handle h over to the right carries with it the gear g , which in turn causes a rotation to the left, as seen in Fig. 2, of the 110 gear g^2 , and also causes the rack a' to move to the right, as seen in Fig. 2. The rotation of the gear g^2 over to the left is imparted to the gear g^3 until that portion of the gear g^2 where the teeth are omitted comes opposite 115 the gear g^3 . At this time, however, the locking-sector q^2 has so engaged the concave portion of the periphery of the locking-sector q' as to prevent a backward rotation of the gear g^3 , thus holding the brakes firmly in the position to which they have been carried by the rotation of this gear g^3 . A further rotation 120 of this gear g^3 over to the left by the movement of the handle h over to the right does not cause any further rotation of this gear g^3 until that portion of the gear g^3 (seen to the right of the sector q^2 in Fig. 2) comes opposite the gear g^3 . Just as the blank section on the periphery of the gear g^2 comes opposite the gear g^3 and just as the locking-sector q^2 engages the locking-sector q' the left-hand end of the slot i' in the rack-bar 130 a' engages the left-hand pin l , projecting from the contact-bar a^2 , so that from this point on

the rotation of the handle h results in a movement to the right of the contact-bar a^2 . This contact-bar a^2 is extended far enough to the left, as indicated in Fig. 2, so that such bar 5 shall always remain in contact with the contact-point s' from the commencement of the movement to the right of such contact-bar a^2 until such bar has reached its extreme right-hand position. The arrangement is such, as 10 will at once be seen, that the rotation of the handle h from its starting position over to the right results, first, in bringing the contact-shoes f firmly up against the wheels W , where they are firmly held at first by the locking-sector q^2 engaging the locking-sector q' . A 15 further rotation of the handle h over to the right serves to cut in *seriatim* the energizing-coils $M' M^2 M^3 M^4$ of the magnets contained in the case C, the action of which is to increase 20 very greatly the pressure of the shoes f upon the wheels W , without, however, applying any braking effort by means of the hand-operated mechanism until all of the energizing-coils contained in the case C have been cut into 25 operative circuit. Then a still further movement of this handle over to the right, while in no way affecting the electrically-operated braking mechanism, which remains at its maximum, serves to apply the full power of 30 the hand-operated braking mechanism. This sequence of events is of course inverted upon a reverse movement of the handle h . A rod a^3 is arranged to be actuated by means 35 of the magnets and armatures in the case C, in the manner to be explained, and is connected with the lever a^4 , pivoted at t^4 . Pivots connected to this lever a^4 is seen a link a^5 of such a conformation that when the rod a^3 is moved to the right by means of the mechanism 40 in the case C this link a^5 is moved first upward by sliding upon the fixed pin e' , and then to the right, all as seen in Fig. 2. The lever a^6 is moved over to the left on the pivot t' during the first part of the motion of the 45 handle h and before the mechanism in the case C is actuated, which results in the pin e being moved just to the right of the hook formed on the upper surface of the link a^5 before this link a^5 is operated. Thus by means 50 of the normal operation of the link a^5 the lever a^6 is engaged, and as the rod a^3 is moved to the right a braking effort is applied to the wheels of the car through the mechanism already described. The result of this construction, 55 it will at once be seen, is that when the electrically-operated mechanism is not operating it is entirely detached from the braking mechanism of the car and the amount of motion to be provided for in the electrically-operated mechanism is thereby greatly lessened. Upon the return of the braking mechanisms to their normal positions (indicated in 60 Figs. 1 and 2) the link a^5 is returned to the position shown in Fig. 2 by engaging the fixed pin e' , seen at the left-hand end thereof.

I will now describe the system of magnets

and armatures contained in the case C, reference being had to Figs. 3, 4, and 5.

A series of cup-shaped magnets $m' m^2 m^3 m^4$ are provided with ears extending to the right and to the left from their upper and lower ends. These ears are so formed upon the magnets $m' m^2 m^3 m^4$, as indicated partially in the case of the magnet m^3 in Fig. 5, that such magnets may be first inserted between either of the rods a^{10} and an adjacent rod a^{11} and then turned slightly so that the notches in the ears will engage the rods a^{11} , when the openings in such notches may be closed by means of plates, as indicated at v^3 in Fig. 5, whereby the magnets $m' m^2 m^3 m^4$ are securely held upon the rods a^{11} . For securing these magnets $m' m^2 m^3 m^4$ in any desired position longitudinally upon the rods a^{11} I make use of split clamping-pieces $k' k^2 k^3 k^4$, arranged by means of screws to be rigidly clamped in the manner indicated to such rods a^{11} . These clamping-pieces $k' k^2 k^3 k^4$ are arranged to fit nicely between the ears on the magnets $m' m^2 m^3 m^4$, respectively, whereby such magnets are held in any desired position longitudinally on the rods a^{11} . A similar means for supporting the armatures $d' d^2 d^3 d^4$ from the rods a^{10} is noted in Fig. 4. It is desirable, however, that these armatures $d' d^2 d^3 d^4$ shall be capable of longitudinal movement upon the rods a^{10} . For that reason clamping-pieces $j' j^2 j^3 j^4$ are provided on one side only of the armatures $d' d^2 d^3 d^4$ in such a way, as clearly indicated also, that while each armature is being operated by its corresponding magnet it forces the rods a^{10} through the openings in the ears on the armature or armatures of the preceding or lower magnet or magnets. Each armature, however, as it is drawn toward its magnet serves to move the rods a^{10} a short distance downward in Figs. 3 and 4 or to the right in Figs. 1 and 2, whereby there is successively applied to the rods a^{10} the motion of each of the armatures $d' d^2 d^3 d^4$, acting *seriatim*, the maximum movement of the rods a^{10} being that required to bring the armature d^4 from the position indicated in Figs. 3 and 4 into contact with its corresponding magnet. The rods a^{11} are suitably secured to the ends of the case C. Suitably secured upon these rods a^{11} and within the case C are seen two plates l' , through which holes are provided for the longitudinal movement of the rods a^{10} in such a way that such rods a^{10} are guided in their longitudinal movement by these plates l' . These rods a^{10} are connected together at their upper ends by means of a bar i , to which in turn there is rigidly secured, by means of threads and nuts, in the manner indicated in Figs. 3 and 4, the right-hand end of the rod a^3 , as seen in Figs. 1 and 2, by means of which the movement of the armatures $d' d^2 d^3 d^4$ is imparted to the system of levers already described, and finally therethrough to the brake-beam a^8 , in the manner already fully described. A rod a^9

leads to the other end of the car for performing the same functions as are performed by the rod a .

In operating my braking mechanism the handle h , as will be at once understood, first applies a braking effort through the chain c , connected to the lower end of the brake-spindle b' and the rod a , connected to such chain and also to the lever a^6 , the motion of which 5 in turn, by means of the connecting-link a^7 , is imparted to the brake-beam a^8 . The arrangements and proportions are such that by the time the bar a' has been advanced by means of the coöperation between the gear g 10 and the rack g' on such bar, so that the left-hand end of the slot l engages the left-hand pin l on the contact-bar a^2 , there has been applied to the wheels W a moderate braking effort through the hand-operated braking mechanism, in the manner already described, which may be just sufficient to bring the 15 brake-shoes f firmly up against the wheels W . At this time the locking-sector q^2 engages the locking-sector q' in such a way as 20 to prevent the backward movement of the brake-spindle b' , while a still further forward movement of the handle h applies only the 25 braking effort through the electrically-operated mechanism, in the manner already explained, until all of the energizing-coils M' 30 $M^2 M^3 M^4$ of the electrically-operated braking mechanism have been cut into circuit. Then at this time the locking-surfaces q^2 and q' are 35 disengaged, and the further movement of the handle h serves to apply a braking effort through the hand-operated mechanism, while the electrically-operated mechanism remains 40 at its maximum. This last application of the hand-operated mechanism I have found very desirable in the case of a failure from any cause of the electrically-operated braking mechanism.

Attention is called to the fact that in the electrically-operated braking mechanism 45 each coil is subjected to the full potential of the source of electricity B , whatever it may be, and that any desired number of the energizing-coils may be cut into circuit and that there is no tendency to apply the brake-shoes 50 more forcibly than they are applied by the last armature coming in contact with its magnet. By this arrangement I have found that the brakes may be much more satisfactorily applied in extreme conditions—that is, a very 55 heavily-loaded car or a car that is very lightly loaded—in this much, that the difficulties resulting from a series arrangement of the energizing-coils are largely overcome by placing the coils in multiple or parallel. In the 60 series arrangement there is a strong tendency to draw the brake-shoes clear up to the point where the last armature comes in contact with its corresponding magnet. This often-times results in a skidding of the wheels, 65 while with the arrangement herein shown and described the tendency to effect a maxi-

mum movement of the brake-beam may be avoided.

What I claim is—

1. In combination with a hand-operated 70 braking mechanism and a handle or lever for operating the same, an electrically-operated braking mechanism, and means whereby the movement of such handle first applies a moderate braking effort by means of the hand-operated braking mechanism, and then cuts into operative circuit the energizing coil or coils of the electrically-operated braking mechanism, and gradually increases the braking effort of the electrically-operated braking 75 mechanism without adding to the braking effort of the hand-operated braking mechanism.

2. In combination with a hand-operated 80 braking mechanism and a handle or lever for operating the same, an electrically-operated braking mechanism, and means whereby the movement of such handle first brings the brake-shoes firmly against their coöperating braking-surfaces by means of the hand-operated 85 braking mechanism, and then cuts into operative circuit the energizing coil or coils of the electrically-operated braking mechanism, and gradually increases the braking effort of the electrically-operated braking 90 mechanism without adding to the braking effort of the hand-operated braking mechanism.

3. In combination with a hand-operated 95 braking mechanism and a handle or lever for operating the same, an electrically-operated braking mechanism, means whereby the movement of such handle first applies a moderate braking effort by means of the hand-operated braking mechanism, and then cuts into operative circuit the energizing coil or coils of the electrically-operated braking 100 mechanism, and gradually increases the braking effort of the electrically-operated braking mechanism without adding to the braking effort of the hand-operated braking mechanism.

4. In combination with a hand-operated 105 braking mechanism and a handle or lever for operating the same, an electrically-operated braking mechanism, means whereby the movement of such handle first brings the 110 brake-shoes firmly against their coöperating braking-surfaces by means of the hand-operated braking mechanism, and then cuts into operative circuit the energizing coil or coils of the electrically-operated braking 115 mechanism, and gradually increases the braking effort of the electrically-operated braking mechanism without adding to the braking effort of the hand-operated braking mechanism, and means whereby the further movement of such 120 handle, after the maximum braking effort has been applied by the electrically-operated mechanism, increases the braking effort applied by such hand-operated braking mechanism.

125

4. In combination with a hand-operated braking mechanism and a handle or lever for operating the same, an electrically-operated braking mechanism, means whereby the movement of such handle first brings the 130 brake-shoes firmly against their coöperating braking-surfaces by means of the hand-operated braking mechanism, and then cuts into operative circuit the energizing coil or coils of the electrically-operated braking mechanism, and gradually increases the braking effort of the electrically-operated braking mechanism without adding to the braking effort of the hand-operated braking mechanism, and means whereby the further movement of such 135 handle, after the maximum braking effort has been applied by the electrically-operated

mechanism, increases the braking effort applied by such hand-operated braking mechanism.

5. In a braking system a series of magnets and their armatures arranged at increasing distances from their corresponding magnets, means whereby the effort exerted between such magnets and their armatures is applied to the brakes, means whereby, as the brakes are moved under the influence of the attraction of such magnets for their armatures, such armatures contact with their corresponding magnets *seriatim* in a way to constitute a magnetic ratchet, and means whereby the

energizing-coils of such magnets may be cut 15 into operative circuit *seriatim* beginning with the magnet whose armature is nearest thereto, and each one of such magnets retained in its operative circuit until, at the time of the release of the brakes, all the energizing-coils of such magnets that have been cut into circuit are cut out of circuit *seriatim* in the reverse order. 20

ANTON DUPPLER.
